UNITED STATES PATENT OFFICE.

AUSTIN TERRYBERRY, OF DULUTH, MINNESOTA.

SECTIONAL FIRE GRATE.

Application filed September 12, 1919. Serial No. 323,273.

To all whom it may concern:

Be it known that I, AUSTIN TERRYBERRY, a citizen of the United States, residing at Duluth, in the county of St. Louis and State 5 of Minnesota, have invented certain new and useful Improvements in Sectional Fire Grates; and I do hereby declare the following to be a full, clear, and exact description of the invention, such as will enable others 10 skilled in the art to which it appertains to make and use the same.

This invention relates to grates and although more particularly applicable to grates around a water conduit, is not limited thereto.

An object of this invention is to provide a grate of an improved and simplified structure that will be fireproof and durable and susceptible of easy and economical assembly and repair.

A further object of this invention is to provide a sectional grate with sections of an improved and simplified structure.

The invention consists in the novel structure and arrangement and combination of parts as hereinafter more particularly described and claimed.

Figure 1 is a side elevation of the right hand grate section;

30 Fig. 2 is a side elevation of the left hand grate section;

Fig. 3 is a cross section through assembled sections without the supporting pipe and shows the tenons of each section;

35 Fig. 4 is a side elevation of two sections assembled on a pipe, the latter in cross section;

Fig. 5 is a side elevation of a water pipe with grate sections mounted thereon, and

40 Fig. 6 is a plan view of the boiler showing a series of pipes with my grates mounted thereon.

In the accompanying drawings it will be noted that each section comprises in detail 45 a body member having a pair of wings 2 projecting in opposite directions from the body, each section being provided on one face with tenons 3 and 4 and a slot 5 communicating with a semicircular opening in the body of each section, the opposite faces of the body being provided with mortises 3' and 4' arranged in transverse alignment with the tenons 3 and 4, so that when the sections are fitted together as illustrated in 50 Figs. 3 and 4, the tenons 3 and 4 of one section will fit into the mortises 3' and 4' of the

next adjacent section. On one side of each section portions of the body are cut away as shown at *a* and *b*, so that when the sections are fitted together, the tenons fitting 60 into the mortises, a space is left between the wing portions 2 of adjacent sections, this space being provided to allow the ashes to drop through the grate.

Each section is mounted on the pipe P by 65 having the side portions of the slot 5 passed over the pipe until the pipe is seated within the arcuate openings within the body of the sections, the sections being alternately faced in opposite directions to bring the slots 5 70 successively on opposite sides of the pipe. The sections are then closed together so that the tenons 3 and 4 are engaged and mate with the mortises 3' and 4', as is clearly illustrated in Fig. 3.

75 The purpose of tenons 3 and 4 is to hold the sections in place upon the pipe P and also to prevent them from relatively turning when the grate is being shaken.

At the end of the series of sections I use 80 a special section which is extended into the form of a crank or arm; this is to provide means for shaking the grate unit.

A spacing bar 7 may be arranged at each end of the series of sections to retain them 85 in position upon the pipe.

Modifications in the precise form and construction will readily suggest themselves to those skilled in the art but within the scope of the present invention as claimed.

90 Having thus fully described my invention, I claim:

1. The combination of a supporting member and a plurality of grate sections, each of said grate sections comprising a body, wings 95 extending from opposite edges of the body, said wings being thinner than the body, each body having a central opening communicating by a slot with one edge adjacent a wing, and said bodies being further provided with mortises on one face and tenons on the other face, said mortises and tenons being arranged on the respective faces of the sections which are to be mounted adjacent each other so that the tenons of one 100 section will mate with the mortises of the next adjacent section when said sections are arranged with their slotted edges facing in opposite directions.

2. The combination of a fixed supporting 110 member and a plurality of substantially U-shaped grate sections, said U-shaped sec-

tions being adapted to be slipped over the supporting member from opposite sides, and mortise and tenon means carried by each of said sections to interlock the same to prevent independent rotary or radial movement of any section, the assembled sections being rotatable upon said supporting member.

3. The combination of a supporting member and a plurality of substantially U-shaped grate sections, each section having laterally extending wings, said wings being thinner than the body of the U-shaped member, said U-shaped members being adapted to be slipped over the supporting member from opposite sides with said wings in alignment and interlocking means to prevent independent rotary or radial movement of any section.

4. The combination of a tubular supporting

member and a plurality of interlocking 20 grate sections, each grate section comprising a U-shaped body the opening of which is downwardly inclined, laterally extending wings, and mortise and tenon means on its opposite faces respectively, whereby radial 25 and rotary movement between the sections is prevented.

5. In a device of the character described, an interlocking grate section comprising a substantially U-shaped body having the 30 opening inclined downwardly, relatively thin wings extending substantially horizontally, and mortises and tenons on its opposite faces respectively as and for the purposes specified.

In testimony whereof I affix my signature,

AUSTIN TERRYBERRY.
